DESIGN FOR A PIPE RACK

Frederic H. Fisher, Syracuse, N. Y., assignor to
Syracuse Ornamental Co. Inc., Syracuse, N. Y.,
a corporation of New York

Application May 10, 1946, Serial No. 129,522

Term of patent 7 years

(Cl. D85—8)

To all whom it may concern:

Be it known that I, Frederic H. Fisher, a citizen of the United States, residing in Syracuse, in the county of Onondaga and State of New York, have invented a new, original, and ornamental Design for a Pipe Rack, of which the following is a specification, reference being had to the accompanying drawing, forming a part thereof.

Fig. 1 is a side perspective view of a pipe rack showing my new design; and

Fig. 2 is a top perspective view thereof.

I claim:

The ornamental design for a pipe rack, substantially as shown.

FREDERIC H. FISHER.
